AMUSEMENT DEVICE

Luther H. Smith, Murrells Inlet, S. C.

Application February 26, 1937, Serial No. 128,003

2 Claims. (Cl. 273—98)

My invention relates to a device for use as a toy or game implement.

An important object of the invention is to provide a device of the above mentioned character which is interesting and amusing to operate or play and which may be played with different degrees of success, depending upon the skill of the operator.

A further object of the invention is to provide means for holding the ball to the frame of the implement when the implement is not in use.

Other objects and advantages of the invention will be apparent during the course of the following description.

15 In the accompanying drawing forming a part of the application and in which like numerals are employed to designate like parts throughout the same,

Figure 1 is a perspective view of a toy or game implement embodying my invention.

Figure 2 is a transverse section taken on line 2—2 of Figure 3.

Figure 3 is a plan view of the device.

Figure 4 is a longitudinal section taken on line 25 4—4 of Figure 3, and,

Figure 5 is a similar view showing the ball anchored to the frame.

In the drawing, wherein for the purpose of illustration is shown a preferred embodiment of 30 my invention the numeral 10 designates a frame, which is preferably annular and this frame is preferably formed integral with a handle 11. The frame and handle are preferably formed from a flat sheet, which may be wood, metal, or 35 composition. At the union of the frame and handle is an enlarged portion 12, diverging toward the frame, and this enlarged portion has a recess or pocket 13 formed therein, the open end of this recess leading into the opening of 40 the frame 10.

The numeral 14 designates an elastic band, formed of rubber or other suitable material. The free ends of the elastic element or band 14 are attached to the frame 10 at diametrically opposite points by staples 15 or any other suitable means. Attention is called to the fact that the longitudinal axis of the recess or pocket 13 is in alignment with the longitudinal axis of the handle 11 and the staples 15 are preferably 90 degrees from the longitudinal axis of the pocket 13. A ball 16 is provided, which is preferably resilient and is preferably formed of rubber and this ball has an opening extending diametrically therethrough to receive the elastic band 14. Particular attention is called to the fact that the

staples 15 are arranged within the main opening of the frame 10 and since the ball receiving recess 13 leads into this main opening, the ball 16 may be inserted downwardly into the recess 13 a sufficient distance, Figure 5, so that the elastic band will be arranged entirely within the main opening of the frame and the recess 13.

In the use of the implement, the operator or player holds the handle 11 in his hand and the implement is reciprocated, such as in a vertical 10 direction. This causes the ball 11 to travel more or less vertically through the opening of the frame 10 and the ball passes to the opposite sides of the frame. By acquired skill, the ball may thus be made to pass freely through the frame 15 10 without contacting therewith. However, this operation cannot be easily effected without considerable practice. In order that the life of the elastic band 14 may be prolonged, the recess or pocket 13 is provided, and when the device is not 20 in use, the ball is forced into the recess or pocket 13 and will be securely held therein against accidental displacement. A further advantage in thus securing the ball to the frame, when the device is not in use, is that such devices may be 25 assembled or stacked in superposed relation, as for the purpose of shipment, and may be removed without liability of the elastic bands becoming entangled with each other. This is accomplished, since when the ball 16 is held within the 30 recess or pocket 13, the positions of the elastic band upon opposite sides of the ball 16 are held substantially taut or free from any substantial slack, as is clearly shown in Figure 5. The portions of the elastic band upon opposite sides of 35 the ball 16 are of substantially the same length, as clearly indicated in Figure 2.

It is to be understood that the form of my invention herewith shown and described is to be taken as a preferred example of the same and 40 that various changes in the shape, size, and arrangement of parts may be resorted to without departing from the spirit of my invention or the scope of the subjoined claims.

Having thus described my invention, what I 45 claim and desire to protect by Letters Patent is:

1. An amusement device comprising a frame having a handle and a main opening, said frame being provided with a ball receiving recess having an open side which leads into the main opening, 50 an elastic band secured to the frame at opposed points, said points being spaced substantially equal distances from the ball receiving recess, a ball secured to the elastic band with portions of the elastic band upon opposite sides of the ball 55

- being of substantially the same length, the arrangement being such that the ball may be inserted within the ball receiving recess and the portions of the elastic band upon opposite sides of the ball will be held substantially taut.
5. 2. An amusement device comprising a handle, a wide frame having a main opening, an enlarged portion connecting the handle and wide frame, said enlarged portion having a ball receiving recess arranged next to the handle, the ball receiving recess having its open side leading into the main opening of the frame, an elastic band, attaching elements arranged within the main

opening of the frame and disposed at substantially equal distances from the ball receiving recess and connecting the ends of the band with the frame, and a ball secured to the elastic band with portions of the elastic band upon opposite sides of the ball having substantially equal lengths, the arrangement being such that the ball is adapted to be inserted within the ball receiving recess and held thereby and the portions of the elastic band upon opposite sides of 10 the ball will be held substantially taut and within the main opening.

LUTHER H. SMITH.
